UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Application filed September 1, 1927. Serial No. 216,840.

My invention relates to rail anchors and has for its principal object the provision of an improved anchor device which is so constructed as to simplify the manufacture of 5 the device and which when applied to a rail will maintain its hold thereon by reason of a relatively rigid part of the anchor having a tight frictional grip on the rail base and by the spring pressure exerted against the 10 rail base by a part of the anchor device.

A more specific object is to provide an improved two-piece anchor, the parts of 15 which may be formed from flat metal blanks cut from relatively narrow strips of metal stock without appreciable waste of material and which when bent to their completed forms and assembled are held engaged by the resiliency of one of the members.

A further specific object is to provide a 20 two-piece anchor in which the member employed to resist the creeping pressure of the rail is relatively rigid and non-yielding and in which the member for retaining the gripping member in its operative position on 25 the rail is so formed as to yield transversely of the rail so as to accommodate the anchor to rail base flanges of different widths and to insure a tight grip transversely of the rail.

30 The invention has for a still further object such other new constructions and arrangements of parts hereinafter described and claimed for carrying out the above stated objects and such other incidental objects 35 as will appear from the detailed description of the embodiment shown in the accompanying drawings.

In the drawings:

40 Fig. 1 is a cross section through the base portion of a railroad rail showing a rail anchor device constructed in accordance with my invention in the process of being applied to the said base flange.

Fig. 2 is a view similar to Fig. 1 showing 45 the anchor device in its applied position.

Fig. 3 is a plan view of the anchor device with a part of the jaw member in section. This view is taken on line 3—3 of Fig. 1 looking in the direction indicated by the 50 arrow.

Fig. 4 is a view in perspective, with parts broken away for the purpose of clearness, of the jaw member of the anchor device shown in the preceding figures.

55 Fig. 5 is a view in perspective of a trans-

verse bar member employed to retain the rail gripping jaw member in its applied position, and

Fig. 6 is a flat view of a sheet metal blank from which the jaw member shown in Fig. 4 60

is formed.

The embodiment of the invention shown in the accompanying drawings consists of a rail gripping member 10 adapted to be driven transversely of the rail into engagement with one flange of the rail base 11, and a retaining member 12 which extends across beneath the rail base and engages with the edge of the base flange at the opposite side 65

of the rail.

The gripping member is made from a flat metal blank 13 of the configuration shown in Fig. 6. The blank may be made of any suitable material. Preferably, it is made of 70

spring metal and is formed of such proportion that it can be sheared from a metal strip having a width corresponding to one dimension of the blank. The said blank is sheared intermediate its ends to provide a central tongue portion 14 and recesses 15 and 75

16 which define the rail gripping surfaces 17 and 18 of upper and lower jaws 19—20 and 21—22. The ends of the blank are bent along the dotted lines 23 and 24 (Fig. 6) 80

until the ends or jaw portions 25 and 26 of 85 the blank stand at substantially right angles to the central portion 27 of the blank. The tongue portion 14 is bent down to a position substantially at a right angle to the central portion 27 and provides a seat on which one 90

end of the retaining member 12 bears when the parts of the anchor are assembled. Preferably the tongue 14 in the finished 95

form of the gripping member, extends between the jaw portions 25 and 26 and is so disposed with relation to the rail gripping surfaces 18—18 of the lower jaws that when 100

the retaining member is in place and the anchor is free of the rail, the upper surface of the retaining member will project slightly above the gripping surfaces 18—18 of the lower jaws. With such construction the tongue portion is depressed slightly and consequently forces the retaining member up 105

against the bottom of the rail base when the jaws 19—20 and 21—22 are driven to their operative gripping positions on the rail. The jaw portions are so spaced with relation to each other longitudinally of the rail as 110

to exert sufficient spring clamping action on 115

the edges of the retaining member 12 to hold the retaining member in its normal assembled position between the said jaw portions when the anchor is free of the rail, thereby providing in effect a one-piece anchor device. The jaw portions preferably stand perpendicular to the bottom surface of the rail base and the gripping surfaces 17-18 bear flat against the top and bottom surfaces of the rail base so as to provide a tight wedging engagement with said rail base when the gripping member is in its applied position.

The retaining member consists of a flat metal strip, preferably spring steel, formed at one end with an upturned flange 28 providing a locking shoulder for engagement with one edge of the rail base. The other end is formed with a downturned loop portion 29 the extremity 30 of which preferably fits between the jaw portions 25, 26 of the gripping member and bears against the end of the tongue 14. The distance between the extremity 30 of the loop 29 and the upturned end 28 of the member 12 is normally such that, with the said loop in engagement with the tongue 14 of the gripping member and the said gripping member driven to its operative position on the rail base, it is necessary to partially close the loop to engage the flange 28 over the edge 31 of the rail base. The distortion of the loop portion provides sufficient spring pressure transversely of the rail to retain the gripping member in its tight gripping engagement with the rail base. The said loop may be made of any suitable size or shape to provide the desired spring pressure or to accommodate the anchor to rails having base flanges of different widths. In the embodiment illustrated, the loop is so formed that the portions 32 thereof project beyond the outer edges of the jaw portions 25 and 26 of the gripping member so as to provide a relatively wide surface for receiving the hammer blows during the application of the anchor to the rail.

In operation the retaining member 12 is engaged with the gripping member 10 at the factory, it being necessary to spread the jaw portions 25 and 26 to permit the insertion of the member 12 between them. The spring pressure of the jaws 25 and 30 is sufficient to prevent disengagement of the members 10 and 12.

The anchor is applied to the base flange of the rail by hooking the jaw portions of the gripping member over one flange of the rail base as shown in Fig. 1 of the drawings. The loop portion 32 of the retaining member may then be struck with a sledge or suitable implement to force the jaws 19, 20 and 21-22 into tight wedging engagement with the top and bottom surfaces of the rail base. That is to say, to the position shown in Fig. 2. When the gripping member 10

has been driven to the limit of its applying movement the upper edge of the flange 28 preferably stands a short distance to the right of the edge 31 of the rail base as shown in dotted lines in Fig. 2. Further driving force delivered against the loop portion 32 distorts the loop sufficiently to permit the flange 28 to snap over the edge 31 of the rail base. The distortion of the loop end of the retaining member sets up a spring pressure transversely of the rail while the depression of the spring tongue 14 from the position indicated in Fig. 1 to the position of Fig. 2 exerts pressure vertically of the rail base.

From the above description of the construction and operation of the embodiment shown in the accompanying drawings it will be seen that I have provided a two-piece rail anchor which may be shipped and applied as a one-piece anchor and which when applied grips the rail with a strong frictional grip and by a spring pressure exerted both vertically and transversely of the rail. In this connection it will be noted that the spring pressure transversely of the rail is produced by reason of the configuration of the separately formed retaining member 12.

It will also be noted from an inspection of the drawings in connection with the above description that the gripping member may be applied to either side of the rail base and positioned to bear against either of two adjacent ties so as to resist creeping movement of the rail in either direction. The relatively wide jaw portion provides bearing faces of sufficient width to avoid damaging the ties, all of which advantages are provided by a simplified form of device of the two-piece type.

I claim:

1. A rail anchor comprising a rail gripping member for engagement with one flange of a rail base, and a retaining bar formed to bear against the bottom surface of the rail base for a substantial distance transversely of the rail and engaging said gripping member and the opposite edge of the rail base and adapted to yield transversely of the rail to permit said engagement of said bar with the rail base.

2. A rail anchor comprising a rail gripping member formed with spaced jaw portions for engagement with one flange of a rail base, and a retaining bar gripped resiliently between said jaw portions and engaging the opposite edge of the rail base and adapted to yield transversely of the rail to permit said engagement of said bar with the rail base.

3. A rail anchor comprising a rail gripping member formed with spaced jaw portions for engagement with one flange of a rail base, a retaining bar extending between said jaw portions and engaging the opposite

edge of the rail base and adapted to yield transversely of the rail to permit said engagement of said bar with the rail base, and means on said gripping member for forcing the retaining member into frictional engagement with the bottom surface of the rail base.

4. A rail anchor comprising a rail gripping member formed with spaced jaw portions for engagement with one flange of a rail base and disposed normally perpendicular to the bottom surface of the rail when in their applied positions, a retaining bar clamped between said portions and engaging the opposite edge of the rail base and adapted to yield transversely of the rail to permit said engagement of said bar with the rail base, and means on said gripping member for forcing the retaining member into frictional engagement with the bottom surface of the rail base.

5. A rail anchor comprising a rail gripping member formed with spaced jaws for gripping one flange of the rail base and a spring tongue disposed between said jaws and adapted to be depressed in applying said jaws to their operative positions, and a separately formed retaining member positioned between said jaws and adapted to be forced transversely of the rail into engagement with the edge of the other flange of the rail base.

6. A rail anchor comprising a rail gripping member formed with spaced jaws for gripping one flange of the rail base and a spring tongue disposed between said jaws and a separately formed retaining member positioned between said jaws and adapted to be forced transversely of the rail into engagement with the edge of the other flange of the rail base; the arrangement of said spring tongue and the retaining member being such that the retaining member is held in frictional engagement with the bottom of said rail base by the resiliency of said tongue.

7. A rail anchor comprising a rail gripping member formed with spaced jaws for gripping one flange of a rail base and a spring tongue disposed between said jaws, and a separately formed retaining member formed with a bend to provide resiliency transversely of the rail and positioned between said jaws and adapted to be forced transversely of the rail into engagement with the edge of the other flange of the rail base; the arrangement of the said spring tongue and the retaining member being such that the retaining member is held in frictional engagement with the bottom of the rail base by the resiliency of the tongue.

8. A rail anchor comprising a rail gripping member formed with spaced jaws for gripping one flange of the rail base, and a separately formed retaining member formed

at one end with a loop to provide resiliency transversely of the rail and positioned between said jaws and adapted to be flexed by movement of the retaining member transversely of the rail to permit said engagement with the edge of the other flange of the rail base.

9. A rail anchor comprising a rail gripping member formed with spaced jaws for gripping one flange of the rail base in a position to bear against an adjacent cross tie, and a separately formed retaining member formed at one end with a loop the end of which bears against a portion of said gripping member and provides resilience transversely of the rail to permit engagement of the other end of said retaining member with the opposite edge of the rail base.

10. A rail anchor comprising a rail gripping member formed with spaced jaws for gripping one flange of the rail base and a spring tongue disposed between said jaws, and a separately formed retaining member formed at one end with a loop, the end of which bears against the end of said spring tongue and provides resilience transversely of the rail and is positioned between said jaws and adapted to be forced transversely of the rail into engagement with the opposite edge of the rail base.

11. A rail anchor comprising a rail gripping member formed with spaced rail gripping jaws adapted to be driven into flat gripping engagement with the top and bottom surfaces of one base flange of the rail, and a retaining member held between said jaws by spring pressure and adapted to be driven transversely of the rail into engagement with the other flange of the rail base.

12. A rail anchor comprising a rail gripping member formed with spaced rail gripping jaws adapted to be driven into flat gripping engagement with the top and bottom surfaces of one base flange of the rail, and a retaining member held between said jaws by spring pressure and adapted to be driven transversely of the rail into engagement with the other flange of the rail base, one end of said retaining member being formed with a resilient loop engaging said gripping member and formed at the other end with a shoulder adapted to snap up over the edge of the last mentioned flange of the rail base.

13. A rail anchor comprising a rail gripping member formed from a flat metal blank sheared intermediate its ends and bent to provide a centrally disposed tongue portion and spaced rail gripping jaw portions, the latter of which normally stand perpendicular to the bottom surface of the rail base, and a retaining member formed from a metal strip provided at one end with a shoulder for engagement with one flange of the rail base and at the other end with a

loop, the free end of which bears against said gripping member to provide a spring grip transversely of the rail; the said loop end of the retaining member being clamped between the jaw portions of the said gripping member by the resilience of said jaw members.

14. A rail anchor comprising a gripping member for gripping one flange of a rail base, and a separately formed retaining member provided at one end with means for engaging the edge of one base flange of the rail and provided at the other end with means providing a resilient engagement with said gripping member.

15. A rail anchor comprising a gripping member for gripping one flange of a rail base, and a separately formed retaining member provided at one end with means for engaging the edge of one base flange of the rail and provided at the other end with a bent portion providing a resilient engagement with said gripping member.

16. A rail anchor comprising a gripping member for gripping one flange of a rail base, and a separately formed retaining member formed at one end with means for engaging the edge of one base flange of the rail and provided at the other end with a looped portion providing a resilient engagement with said gripping member.

17. A rail anchor comprising a gripping member for gripping one flange of a rail base, and a separately formed retaining member provided at one end with means for engaging the edge of one base flange of the rail and provided at the other end with means providing a resilient engagement with said gripping member; the length of said retaining member being such that it is necessary, in applying the anchor to a rail, to flex said resilient end portion of the retaining member in forcing it into operative engagement with the rail to lock the gripping member in position thereon.

ROLANDIS A. BLAIR.
